UNITED STATES PATENT OFFICE.

THOMAS R. COOK, OF IRVINGTON, ASSIGNOR OF ONE-FOURTH TO HARRY M. BARNARD, HEBER S. PARAMORE, AND GEORGE A. TOPP, OF INDIANAPOLIS, INDIANA.

COMBINED TRY-SQUARE AND BEVEL.

SPECIFICATION forming part of Letters Patent No. 485,456, dated November 1, 1892.

Application filed December 7, 1891. Serial No. 414,277. (No model.)

To all whom it may concern:

Be it known that I, THOMAS R. COOK, a citizen of the United States, residing at Irvington, in the county of Marion and State of Indiana, have invented certain new and useful Improvements in a Combined Rafter-Gage, Try-Square, and Bevel, of which the following is a specification.

The object of my said invention is to produce a tool which will embody the ordinary try-square and bevel, and also a rafter-gage and scale, by which the ends of rafters for any desired pitch of roof may be accurately and conveniently marked for cutting and their length determined, all as will be hereinafter more particularly described and claimed.

Referring to the accompanying drawings, which are made a part hereof, and on which similar letters of reference indicate similar parts, Figure 1 is a plan view of my improved tool as it appears when placed on a rafter ready for use; and Fig. 2, a view of the tool separately, on a somewhat enlarged scale, and in form to be used as a try-square, a fragment 25 of the stock being broken away to show fully the sector and the markings thereon.

In said drawings, the portions marked A represent the blade of the tool, and B the stock pivoted thereto. The blade is in the 30 general form of an ordinary steel square, having two blades running at right angles with each other, but provided with an extension in substantially the form of a sector of a circle on the rear outer side of one of the blades.

35 The stock is pivoted thereto by a pivot b at a convenient point near the outer edge and is grooved and slotted to permit the sector-shaped piece to pass through it and to receive one edge of that blade upon which said sector-shaped piece is formed. The stock being thicker than the blade and projecting on both sides thereof like the handle of an ordinary bevel or try-square is enabled to serve the usual purposes of the stock to such a tool.

40 The sector-shaped extension of the blade has preferably a scale upon its edge marked regularly for the degrees similarly to an ordinary quadrant. It has further markings, which are denominated, respectively, $\frac{1}{4}$, $\frac{1}{3}$, $\frac{2}{3}$, $\frac{3}{4}$, $\frac{5}{8}$, $\frac{7}{8}$, $\frac{9}{8}$, $\frac{11}{8}$, $\frac{13}{8}$, $\frac{15}{8}$, $\frac{17}{8}$, $\frac{19}{8}$, $\frac{21}{8}$, $\frac{23}{8}$, $\frac{25}{8}$, $\frac{27}{8}$, $\frac{29}{8}$, $\frac{31}{8}$, $\frac{33}{8}$, $\frac{35}{8}$, $\frac{37}{8}$, $\frac{39}{8}$, $\frac{41}{8}$, $\frac{43}{8}$, $\frac{45}{8}$, $\frac{47}{8}$, $\frac{49}{8}$, $\frac{51}{8}$, $\frac{53}{8}$, $\frac{55}{8}$, $\frac{57}{8}$, $\frac{59}{8}$, $\frac{61}{8}$, $\frac{63}{8}$, $\frac{65}{8}$, $\frac{67}{8}$, $\frac{69}{8}$, $\frac{71}{8}$, $\frac{73}{8}$, $\frac{75}{8}$, $\frac{77}{8}$, $\frac{79}{8}$, $\frac{81}{8}$, $\frac{83}{8}$, $\frac{85}{8}$, $\frac{87}{8}$, $\frac{89}{8}$, $\frac{91}{8}$, $\frac{93}{8}$, $\frac{95}{8}$, $\frac{97}{8}$, $\frac{99}{8}$, $\frac{101}{8}$, $\frac{103}{8}$, $\frac{105}{8}$, $\frac{107}{8}$, $\frac{109}{8}$, pieces. I prefer to make the blades of the square about eight inches in length, with the right-hand blade about one and three-fourths inches wide and the left-hand blade about one and one-eighth inches wide at its narrow end, with the sector extension substantially in proportion, as shown in the drawings.

Having thus fully described my said invention, what I claim as new, and desire to set 10 cure by Letters Patent, is—

- 15 1. A combined tool, as described, consisting of a square having a projection upon the outer edge of one of its blades, provided with markings corresponding to the various pitches of roof, and a stock pivoted to and adapted to swing over said blade and its projection, whereby rafters can be marked for any required pitch of roof by the use of said tool without calculation, substantially as set forth.
- 20 2. In a combination-tool, a square having a sector-like projection on the outer edge of one blade, provided with markings, as specified, a stock pivoted thereto and adapted to swing over the same, and a table on the other

blade of the square, bearing the same markings in a vertical column, the widths of the building in a horizontal row and the lengths of the required rafters at intersecting points of lines projected from said vertical column and horizontal row, substantially as set forth. 25 30

3. As a new article of manufacture, the tool described, consisting of a combined try-square, bevel, and rafter-gage, the two blades whereof are integral and extend out at right angles with each other and wherein one blade has 35 a projection on its outer edge upon which are desired markings, and a stock pivoted thereto and adapted to swing over said projection and in varying relations to said blade, substantially as set forth. 40

In witness whereof I have hereunto set my hand and seal, at Indianapolis, Indiana, this 30th day of November, A. D. 1891.

THOMAS R. COOK. [L. S.]
